UNITED STATES PATENT OFFICE.

WILLIAM C. HOMAN, OF MERIDEN, CONNECTICUT, ASSIGNOR TO THE
EDWARD MILLER & COMPANY, OF SAME PLACE.

DESIGN FOR A HANGING LAMP.

SPECIFICATION forming part of Design No. 30,725, dated May 9, 1899.

Application filed April 11, 1899. Serial No. 712,670. Term of patent 7 years.

To all whom it may concern:

Be it known that I, WILLIAM C. HOMAN, a citizen of the United States, residing at Meriden, New Haven county, Connecticut, have 5 invented and produced a certain new and original Design for Hanging Lamps, of which the following is a full, clear, and exact description.

My invention relates to a new and original design for a hanging lamp, substantially as shown in the accompanying drawing, in which the figure thereon is illustrative of the same in side elevation.

In said drawing the upper part of the lamp 5 is in the shape of a spherical body A having a depending projection B, the lower end of which is forked, as at C C'. Between the forked ends C C' is an object D, of bell-shaped appearance, the mouth of which opens down-

ward. Across the space between the ends of the forks C C' is a horizontal rod-like member E, pointing toward the end of a curved member F, which is closely adjacent to one end C of the fork. This member F extends downwardly and is curved inwardly, so that 25 the lower end is substantially under the center of the sphere A. At the lower extremity of the curved member F is an upwardly-projecting body G of cylindrical form.

What I claim is—

The design for a lamp substantially as herein shown and described.

Signed at Meriden this 8th day of April, 1899.

WILLIAM C. HOMAN.
